UNITED STATES PATENT OFFICE.

FAYETTE B. BARNARD, OF DAYTON, OHIO, ASSIGNOR, BY MESNE ASSIGNMENTS, TO NATIONAL CASH REGISTER COMPANY, OF JERSEY CITY, NEW JERSEY, A CORPORATION OF NEW JERSEY.

CASH-REGISTER.

SPECIFICATION forming part of Letters Patent No. 707,195, dated August 19, 1902.

Application filed July 11, 1898. Serial No. 685,655. (No model.)

To all whom it may concern:

Be it known that I, FAYETTE B. BARNARD, a citizen of the United States, residing at Dayton, in the county of Montgomery and State of Ohio, have invented certain new and useful Improvements in Cash-Registers, of which I declare the following to be a full, clear, and exact description.

This invention relates to improvements in cash-registers, and has more particular relation to machines of the type employing check and detail strip printers.

The present invention is an improvement on the class of machine patented to Thomas Carney, No. 497,860, dated May 23, 1893, and attention is therefore called to said patent.

One of the several objects of the invention is to provide improved means in a machine of the class mentioned for printing both a check and a detail-record strip.

In the appended drawings, forming part of this specification, Figure 1 represents a top plan view of the devices embodying my invention applied to a machine of the type mentioned. Fig. 2 represents a side elevation of the same. Fig. 3 represents a vertical transverse section through said machine, the drawer and casing being omitted. Fig. 4 represents an enlarged detail side elevation of the ribbon-feeding mechanism. Fig. 5 represents an enlarged detail perspective view of one of the shifting-levers, showing its attachment to the ink-ribbon. Fig. 6 represents an enlarged detail perspective view of the ribbon-feeding slides, and Fig. 7 represents an enlarged detail side elevation of the locking devices shown in dotted lines in Fig. 3.

In the aforesaid drawings, 1 represents the frame of the machine, 2 the keys, and 3 the slidable printing-bars. The construction and operation of the keys and registering and indicating devices is substantially the same as described in the above-mentioned patent, and attention is therefore directed to the same for a detail description of the parts. The said keys in the present instance are divided into three groups or banks representing, respectively, units of cents, tens of cents, and units of dollars; but this capacity may be either increased or decreased without depart-

ing from the spirit of my invention. Each of the aforesaid keys is provided forward of its pivot-point with a laterally-projecting stud 4, which is adapted to pass into an open-ended cam-slot 5, formed in one of a series of plates 6. Each of these slots has an approximately vertical portion 5^a, an inclined portion 5^b, and an end dip 5^c, whereby the keys may move at both ends of their strokes independently of the said plates. The said plates 6 of the units-of-dollars bank are fast upon a transverse rock-shaft 7 and are so arranged in relation to the same that the cam-slots extend at different angles thereto, whereby the said shaft is rocked either to a greater or less extent, according to the value of the key operated. The remaining banks of keys, representing the units of cents and tens of cents, are also provided with similar cam-slotted plates, which are secured, respectively, to nested sleeves 8 and 9, mounted loosely upon each other and upon the shaft 7, so as to be capable of movement independently of said shaft and of each other. Each of said sleeves, as well as the shaft, is provided with one of a series of locking-sleeves 10, fast thereto and formed with a notched lug 11. Each of these lugs is normally engaged and locked in position against movement in either direction by the nose 12 of one of a series of locking-levers 13, said lever being carried by one of a series of yokes 14, pivoted on the key-shaft and extending below its respective bank of keys.

It will be observed from the above that each bank of keys is provided with one of the yokes 14, so that when any key in a bank is depressed it engages its yoke and moves the same downward against the tension of a spring 15, which normally supports it in its upper position, and thus operates its arm 13 to release the operating-shaft 7 or sleeves 8 and 9, as the case may be. By this means the operating-shaft and the two sleeves are positively locked against any accidental or fraudulent movement and cannot be operated until one of their respective keys is partly depressed, said key being prevented from being retracted until it has made its full stroke, as described in the aforesaid patent. The 100

said shaft 7 and sleeves 8 and 9 extend beyond the frame 1 of the machine at one end different distances and are each provided with a rigid arm 16, formed with a longitudinal notch or slot 17 at its outer end. The type-bars 33, which are movably mounted in slotted brackets 18, are each provided with a laterally-projecting stud 19, which projects into the slot 17 of its respective arm 16, so that 5 when the latter is operated the bar will be moved to the necessary extent to bring the desired type into the proper printing position. Each of the said type-bars is formed both top and bottom with printing-type, so that an 10 impression may be secured both above and below the same. In order to secure an inking means for both sides of the bars, I provide an inking-ribbon 19^a and pass the same over antifriction-rollers 20, arranged on opposite 15 sides of said bars and above and below the same. This ribbon passes downward over guiding-rollers 21 and has its respective ends secured to spools or reels 22 and 23, journaled on a frame 24. Each of these reels is provided 20 with a ratchet-wheel 25, by means of which it is fed forward to wind the ribbon thereon. The winding is accomplished by spring-pressed pawls 26, mounted on a slide- 25 able cross-bar 27, which in turn is loosely mounted in a vertical slide 28. This vertical 30 slide is suitably mounted in the frame 24 and is provided at its upper end with an angular slotted arm 29, which will be hereinafter more particularly described. The lower portion 35 of the vertical slide is formed with a transverse groove 30, in which the said bar 27 is loosely mounted, so as to be capable of sliding horizontally. The pawls 26 are limited in their movements and prevented from being 40 forced too far forward under the tension of their respective springs 31 by lugs 32, with which they are provided, contacting with stop-pins 33, mounted on the slide 27. The 45 relative arrangement of the said pawls and stops is such that when one pawl is engaging its ratchet-wheel 25 the other will be disengaged from its ratchet-wheel. In order to prevent any backward movement of the said ratchet-wheels, two gravity-pawls 34 are 50 pivoted on the frame 24 in proximity to the said wheels and are arranged to be withdrawn from contact with said wheels by pins or studs 35, mounted on the slide 27. When 55 said slide is moved in one direction, one of said pins 35 disengages from its pawl 34 and allows the latter to fall into engagement with its ratchet-wheel, while the remaining pin 35 engages the remaining pawl and forces it out of engagement with its ratchet-wheel. The 60 structure of said pawls is such that the predominating weight of each is thrown to one side of its pivot-point, and said pawl thus held to engagement with its wheel by gravity. The aforesaid slide 27 is moved from 65 one side to the other to reverse the movements of the inking-ribbon by a lever 36, mounted on the frame 24 and provided with

an operating-pin 37, which extends through a suitable slot formed in the frame and enters a vertical groove 39, formed in said slide 27. 70 The upper end of the lever 36 is formed with two diverging arms 40, which are arranged to be struck and operated by pivoted arms 41, mounted on the respective reels 22 and each provided with a pin 42, to which the end of 75 the ribbon is attached, said pin working through a slot in one of the reel-flanges. When the ribbon has become exhausted from one of the reels, its respective arm 41 is drawn outward and striking one of the arms 40 operates the lever 36 and moves the slide 27 to shift the pawls and cause the ribbon to be reversed. The lower end of the said lever 36 is formed with two spaced notches, into which a teat 43 80 upon the end of a spring-pressed pawl 44, 85 mounted on the frame 24, is adapted to snap, and thus temporarily hold the lever in its adjusted positions. As the slide 28 moves up and down, the pawls 26 are similarly elevated and depressed and operate either one or the other 90 of the said reels, according to the position of the slide 27. This reciprocation of the slide 28 is effected through the medium of the angular slotted arm 29, which projects into proximity to a bell-crank platen-arm 44^a, whereby a pin 45, mounted on said arm, projects into the slot of said slotted arm. The lower portion of said platen-arm is provided with a resilient platen 46, arranged to force the detail-strip into contact with the under side of 100 the type-bars, while the upper portion is formed with an angular slot 47 for the reception of a crank-pin 48, mounted on a crank-arm 49, which in turn is fast upon one of the journal ends of the key-coupler 50. The said 105 platen-lever is further provided with a stud 51, which projects into a slot 52 in the upper platen-lever 53, which is pivoted on the frame and carries a platen 54 similar to the platen 46. It will be observed that by this structure both of the platen-levers are simultaneously operated to bring the respective platens into printing positions. In addition to the stud 51 the lever 44^a is provided with a gravity-pawl 55, which engages a ratchet-wheel 115 56, mounted on a winding-spool 57, which is adapted to receive the record-strip 58 from a supply-spool 59 after said strip has passed over the spool-supporting bracket 60. Any 120 backward movement of the spool 57 is prevented by a hook-pawl 61, pivoted on the frame and engaging the said ratchet-wheel 56.

It will be seen from the foregoing description that upon each operation of the machine both the inking-ribbon and the record-strip 125 are moved forward one step, so as to be ready for the succeeding operation of the machine. When it is desired to print a check as well as the detail-strip, a suitable check is inserted in an inverted position under the platen 54 130 through a suitable slot in the printer-casing, so as to be forced downward upon the operation of the machine.

I do not care to limit myself to the appli-

cation of my invention to any particular type of registering mechanism, as the same may be applied to operate counters, printing mechanisms, indicators, or any other form of indicating or registering devices without departing from the spirit of my invention.

Having thus described my invention, what I claim as new, and desire to secure by Letters Patent, is—

- 10 1. In a cash-register, the combination with a recording mechanism, of a series of operating-keys, a plurality of graduated plates mounted independently of the keys but so as to be engaged by the same, means connecting the plates to the recording mechanism, and a locking means for said plates for preventing any movement of the same until after the initial movement of a key.
- 20 2. In a cash-register, the combination with a recording mechanism, of a series of operating-keys arranged in banks, cam-plates also arranged in banks and connected to said mechanism and arranged to be engaged by said keys, and an independent locking device for each bank of plates for preventing any movement of the latter until a key in the respective bank is operated.
- 30 3. In a cash-register, the combination with a recording mechanism, of a series of operating-keys arranged in banks, operating devices connected to the recording mechanism and adapted to be engaged by said keys, a pivoted yoke for each bank of keys and arranged to be operated by said keys and a locking means mounted on each yoke and adapted to engage its respective operating device to lock the latter until a key has been operated.
- 40 4. In a cash-register, the combination with a printing mechanism, of an inking-ribbon, winding-reels for said ribbon, devices connected to said ribbon and pivoted on said reels and arranged to be positively moved by the ribbon and feeding means for said ribbon adapted to be shifted by said pivoted devices to reverse the feed.
- 50 5. In a cash-register, the combination with a printing device, of an inking-ribbon, winding-reels for said ribbon, a slide carrying operating means for said reels and means connecting the ribbon to the reels for automatically and positively moving the slide to shift the direction of movement of the ribbon.
- 55 6. In a feeding device for inking-ribbons, the combination with a ribbon, of winding-reels for the same, a slide carrying actuating pawls and means connecting the ribbon to the reels for automatically and positively moving said slide to reverse the feed when the ribbon is exhausted from one or the other reel.
- 60 7. In a feeding device for inking-ribbons, the combination with a ribbon, of winding-reels for the opposite ends of the same, levers mounted on said reels and connected to said ribbon, a winding device for said reels and
- means arranged to be operated by said levers to shift the winding devices.
- 8. In a feeding device for inking-ribbons, the combination with a ribbon, of winding-reels therefor, a slide, operating-pawls for said reels carried by said slide, locking-pawls for said reels and means mounted on the reels and connected to the ribbon for automatically moving said slide to reverse the feed of the ribbon when the ribbon has become exhausted and its tension is exerted on said means.
- 70 9. In a feeding device for inking-ribbons, the combination with a ribbon, of winding-reels for the same, an operating-slide for said reels and a shifting slide mounted on the operating-slide and arranged to be automatically shifted to reverse the feed.
- 80 10. In a feeding device for inking-ribbons, the combination with a ribbon, of winding-reels for the same, movable devices connecting the ribbon to the reels, an operating-slide and means arranged to be struck by the movable devices for shifting said slide to reverse the feed.
- 85 11. In a feeding device for inking-ribbons, the combination with a ribbon, of winding-reels for the same, an operating-slide, means mounted on the reels and connected to the ribbon for shifting the slide to reverse the feed, and a latching device for holding said slide in its adjusted positions.
- 90 12. In a cash-register the combination with a recording mechanism, of a series of graduated cams for operating said mechanism, a series of keys engaging said cams during their full strokes but moving the same different distances according to the formation of the cams, and a locking means for said cams adapted to be released by the operation of a key.
- 100 13. In a cash-register, the combination with a series of keys, of printing devices arranged to be operated by the same, an inking-ribbon, winding-reels for said ribbon, pivoted devices mounted on said reels and connected to said ribbon, and means operated by the printing devices for feeding said ribbon and adapted to be shifted by said pivoted devices to shift the feed.
- 105 14. In a cash-register the combination with a series of keys, of a movable member common to said keys, printing devices arranged to be set by said keys on their downstrokes, a platen operated by the movable member, an inking-ribbon and a slide connected to the platen and arranged to feed the ribbon as the keys and printing devices move back toward normal position.
- 110 15. In testimony whereof I affix my signature in the presence of two witnesses.
- 115 FAYETTE B. BARNARD.
- Witnesses:
- 120 ALVAN MACAULEY,
WILLIAM MUZZY.
